UNITED STATES PATENT OFFICE.

EMILE BACHELET, OF NEW YORK, N. Y.

SYNCHRONIZING-INTERRUPTER FOR ELECTRIC CURRENTS.

986,039.

Specification of Letters Patent. Patented Mar. 7, 1911.

Application filed February 4, 1909. Serial No. 476,054.

To all whom it may concern:

Be it known that I, EMILE BACHELET, of New York, in the county of New York and State of New York, have invented certain new and useful Improvements in Synchronizing-Interrupters for Electric Currents; and I hereby declare that the following is a full, clear, and exact description thereof, reference being had to the accompanying drawings, which form part of this specification.

This invention is an improvement in apparatus for varying the nature and intensity of electric currents; it is especially adapted for use in connection with electrical signaling, wireless telegraphy, and telephony and for electromagnetic therapeutic apparatus, and other purposes in the art, wherein it is desirable to vary the character of the electric current derived from a source of electric energy by interrupting the current at periodic intervals.

The invention is particularly designed and adapted for use in connection with alternating currents and is capable of breaking and interrupting such currents in absolute synchronism with the waves thereof so that perfect and continuous uniformity of action of such current can be obtained.

The invention is also useful for interrupting direct currents.

Another object of the invention is to provide a novel interrupter by which sparking will be reduced to a minimum, or practically obviated, and the main contacts shall be separated with a snap action, and the armature moved away from the magnet with a snap action; and to make these parts so sensitive in operation that they will vibrate in exact unison with the alternations of the current.

I will now describe the invention with reference to the accompanying drawings so as to enable those skilled in the art to make and use the same; and the parts and features for which protection is desired are set forth in the claims.

In said drawings—Figure 1 represents diagrammatically a plan view of the apparatus adjusted for use with alternating currents. Fig. 2 is a detail view showing the switch adjusted for direct currents. Fig. 3 is an enlarged detail view of the preferred form of interrupter. Fig. 4 is a view of a

modification of the interrupter. Fig. 5 is a detail view of another modification of the interrupter.

The mechanical details and arrangements of the elemental parts being varied to suit the constructor, within the scope of my invention, it is therefore unnecessary to show in detail the electrical conductors, switches, lamps and other well known elemental features of construction and therefore the parts are generally illustrated diagrammatically.

In Fig. 1 A designates the main conductor block by which the apparatus can be connected to a source of electricity, such as the main line wires from a generating station. A conductor *a* is connected to one terminal of this connector, and leads to a main switch M. S. so that the current may be cut on or off from the apparatus at will. The conductor *a* is branched beyond the switch, one branch *a'* leading to a binding post *b* which forms part of the interrupter hereinafter described, and through this post is tapped an adjustable contact screw *b'* which is adapted to contact with a block *c'* on a vibratory strip *c* which is strung under tension between two posts *d* and *d'*. The post *d'* is connected by a wire *a''* to one contact point *e* of a double throw switch, which has four blades or closers pivoted at *f*, *f'*, *f''*, *f'''*, intermediate two series of contact points *e*, *e'*, *e''*, *e'''*, and *g*, *g'*, *g''*, *g'''*. When the switch is thrown into engagement with contact points *e*, *e'*, *e''*, *e'''*, it is out of engagement with one of the series of contact points *g*, *g'*, *g''*, *g'''*, and vice versa. The contact post *d'* is also connected by wires *a''*, *a'''*, with the switch point *f'''*.

To facilitate the explanation of the invention I will first describe the apparatus as used with an alternating current, without interruption thereof.

When the double throw switch is closed as indicated in Fig. 1 so as to connect the points *f*, *g*; *f'*, *g'*; *f''*, *g''*; *f'''*, *g'''*; the current passes from post *d'* through wires *a''*, *a'''*, directly to point *f'''*; and thence through the switch blade to point *g'''*; and thence through a wire *a⁴* to one terminal *i'* of a connector block *i* from which it may be taken through suitable conductors, not shown, to any desired receptive device, or to a magnetic generator; and it returns to the other terminal

i^2 of block i and thence passes through wire a^5 to lamp L , and thence through wire a^6 to the terminal A^2 of the block A . A condenser C is connected between the wires a^4 , 5 a^5 , adjacent the connecting block i , as indicated in Fig. 1.

A plurality of receptive devices may be operated in multiple by this apparatus, and, as shown in Fig. 1, I have provided a second 10 connector block j , one terminal j' of which is connected to a wire a^4 by a branch a^8 ; and the other terminal j^2 of block j is connected by wire a^9 to conductor a^6 ; a lamp L' being interposed in branch a^9 . The lamps L , L' , 15 are merely used to introduce resistance into the circuit; and they may be omitted or changed to increase or lessen resistance; and may be substituted by fuse plugs. The foregoing indicates the course of either direct or 20 alternating current through the apparatus when the interrupter is not in operation.

For the purpose of actuating the interrupter so as to break the current at the desired time, the strip c is provided with an 25 armature c^2 , opposite the core, or pole, h' of an electromagnet h . One terminal of this magnet h is connected by a wire h^2 with the switch point f' and the other terminal of the coil is connected by a wire h^3 with the 30 switch point f . The conductor a is connected by a branch a^{10} with the switch point f^2 . A single pole switch S and a lamp L^2 are interposed in the wire a^{10} . The switch points g' , g^2 , are connected by a wire g^4 , and 35 consequently when the switch S is closed and the main switch is thrown so as to connect the points f , f' , f^2 , f^3 , with the points g , g' , g^2 , g^3 , a shunt current will pass from conductor a through wire a^{10} , and points f^2 , g^2 ; 40 g' , f' , and wire h^2 to the coil h , and back through wire h^3 to point f ; thence to g , and then through wire a^{11} to the wire a^6 . The lamp or fuse plug L^2 is used to introduce such resistance into the shunt as may be desired. 45 The function of lamp L^2 is to regulate the amount of current going to the induction coil H when alternating current is used. With the parts thus connected it will be seen that the alternating current can pass 50 through the apparatus from the point A' back to the point A^2 , such current energizing such electroreceptive device as may be connected with the blocks i , j . There is also a shunt current passed through coil h of the 55 interrupter. The parts are so arranged that when this coil h is energized armature c^2 is attracted and the main circuit is broken or interrupted by the separation of the contact points c' , b' . The coil being energized by an 60 alternating current the armature will be attracted at the high and low points of the current waves; but will be released at the neutral points, and consequently the main circuit will be broken at the maximum of 65 each current wave or pulsation; but the

armature is also released at each neutral point of the current pulsation; I believe the main circuit is interrupted at or about the extreme points of each alternation in the current, and is closed at each neutral point 70 in the current alternation. In order to insure this action the interrupter is of peculiar novel construction as hereinafter pointed out. The alternating current is interrupted in exact synchronism with its alternations 75 with the result that at each break there is a greatly accentuated wave of current. Such an interrupted alternating current will be particularly useful in wireless telegraphy and telephony because of its greatly increased intensity and its absolute regularity and uniformity. The interruptions are absolutely synchronous with the alternations of the current and wholly controlled thereby. 80

If desired a certain amount of uninterrupted alternating current may be sent to the receivers along with the interrupted current by means of a branch wire a^{14} indicated in dotted lines in Fig. 1 leading from the wire a^{10} to the wire a^4 around the switch. 85 A plug a^{15} may be connected in the wire a^{14} so that a lamp or other receptive device may be connected at that point if desired. 90

The interrupter.—The interrupter is of peculiar novel construction; it embodies a 95 strip c secured to and between the posts d , d' , the post d' being slotted to receive one end of the strip c which is secured thereto by a screw d^2 ; and the post d is slotted to receive a slide d^3 to which the other end of the strip c is attached. The slide d^3 is provided with a threaded shank d^4 on which is a hand-nut d^5 by turning which the spring strip can be put under the desired tension sufficient to prevent the armature c^2 being 100 actually drawn into contact with the core h' of the magnet h . The armature c^2 is fast to the spring strip c about midway of its length; while the contact c' is attached to the strip at a point approximately midway between the post d and the armature c^2 . Intermediate the contact c' and armature c^2 I arrange a spring m , one end of which is connected to the strip by preferably insulating material m' ; and the other end of the spring 110 is connected to a slide m^2 engaging a slot in a post m^3 , and fastened in adjusted position by means of a set-screw m^4 . At the opposite sides of the strip is a spring n having one end attached to the strip by a sleeve n' and its other end attached to a slide n^2 passing through slotted post n^3 and fastened by a screw n^4 . The springs m — n 120 act in opposition; the spring n is slightly stronger than spring m and helps the magnet h draw the armature c^2 toward the core h' . This action is resisted by the spring m which tends to keep the contact c' against screw b' until the magnet h is energized 125 with sufficient power to practically snap c' 130

away from b' . The springs m and n will produce a snap break by their tension being regulated so as to make one stronger than the other, which will cause a snap break 5 at any point desired between the minimum and maximum height of the wave. These springs are absolutely necessary to produce this action, as the armature C^2 would not keep in synchronism without them. The 10 tension of the spring strip opposes the action of the spring n and armature h ; and on the initial energization of the magnet the strip will have a tendency to buckle instead of bowing uniformly between the posts d , d' ; the strip will be drawn upwardly at n and c^2 and will be drawn downwardly at 15 the point m' . Consequently c' will not separate from b' on the initial movement of the armature c^2 under the attraction of the 20 magnet h . But ultimately, as the pulsation reaches the maximum, c' will be snapped away from b' and the current interrupted. As soon as the wave of current reaches 25 "zero" spring m snaps contact c' against contact b' and the circuit is again closed. The springs $m-n$ steady the vibratory movements of the strip and cause the armature c^2 to move positively to and from the magnet, and neutralize any tendency to excessive 30 vibration of the armature. The armature c^2 must lie very close to the magnet core but should not be permitted to contact therewith at any time, so that there will be no residual magnetic attraction to be overcome 35 upon the breaking of the current. These springs $m-n$ must be properly adjusted so that they act, as I believe, in the manner above stated, and by their use I am able to obtain absolute synchronism between 40 the interruptions of the current and its alternations. As these alternations occur with extreme rapidity the current must be broken many hundreds of times per second and this could not be accomplished by the ordinary 45 form of interrupter, or by the use of a simple spring contact. In order to prevent sparking from the reaction of the magnet h when the current is broken therethrough, a condenser C of usual construction, may be connected with the post d and b , as indicated in the drawings.

In Fig. 4 I have shown, in place of the spring m Fig. 3, a rubber cushion M contacting with the upper side of the strip c and attached to the end of a screw M' tapped through a post M^2 ; and in place of spring n I have shown a rubber cushion N attached to the screw N' tapped through a post N^2 and bearing against the under side of the strip. These devices act upon the strip in substantially the same way as the springs $m-n$ above described, and I have used such; but I consider the construction shown in Fig. 3 preferable.

When using a direct current the double

throw switch is thrown so as to establish connection between the points $e, f; e', f'$; e^2, f^2 , and break the connection between the points f, f', f^2, f^3 , and g, g', g^2, g^3 , as indicated in diagram Fig. 2. The current then 70 flows through conductors a and main branch a' to the interrupter, switch S being now opened. It then passes through contacts b', c' to post d' ; thence through wire a^2 to point e ; and thence through the double pole 75 switch member to the point f ; thence through the wire h^3 to the coil h , back through wire h^2 to the point f' ; and thence through the double pole switch member back to point e' ; and thence through wire e^7 , connecting the 80 points e', e^2 , through wire e^8 to wire a^4 , and out to the receptive devices as before; and back through the wire a^7 . Obviously as the entire current flows through the interrupter the direct current is broken or intermittent 85 each time the magnet h is energized. If the switch S be closed part of the direct current will pass through the wire a^{10} , to the point f^2 as before; and thence from f^2 through the switch to point e^2 ; and thence 90 through wires e^7 and e^8 to conductor a^3 where it passes on to the receptive devices as before. Thus by use of this device the direct current may be wholly interrupted or a portion of it may be sent interruptedly to the 95 receptive devices.

Another modification of the interrupter is indicated in Fig. 5. The pull spring m being substituted by a presser spring m^6 and the pull spring n being substituted by a 100 push spring n^6 ; the springs m^6 and n^6 having substantially the same effect on strip c as springs m and n . These modifications are shown merely to illustrate the possibility of varying the construction of the interrupter and not to limit the invention.

The purpose for which the apparatus is intended is that of a synchronizing interrupter for the alternating current, or an interrupter for the direct current, for my 110 therapeutic magnetic wave generators. It is also useful for varying electric or magnetic waves for use in wireless telephony or telegraphy.

Having described my invention what I 115 claim as new and desire to secure by Letters Patent is:

1. In an electric current changing apparatus, the combination of an electric circuit, a double throw switch having one series of 120 contacts for alternating currents and another series of contacts for direct currents, an interrupter in the main circuit, and connections whereby the interrupter may be placed in series with the main circuit when direct current is employed, and may be placed in shunt with the main circuit when alternating current is employed.

2. An interrupter for electric current, comprising a strip, a contact point beside 130

said strip, an electromagnet beside the strip adapted when energized to cause the strip to open the circuit, yieldable means engaging said strip and tending to keep the circuit closed, and opposed yieldable means engaging said strip and tending to open the circuit.

3. An interrupter for electric current comprising a tensioned strip, a contact on 10 said strip adapted to be connected in the circuit, a contact point beside said strip also adapted to be connected in the circuit, an electromagnet beside the strip adapted when energized to attract the strip and open the 15 circuit, yieldable means engaging said strip and tending to keep the circuit closed and opposed yieldable means engaging said strip and tending to open the circuit.

4. An interrupter for electric currents, 20 comprising a tensioned strip, a contact point beside said strip, an electromagnet beside the strip adapted when energized to cause the strip to open the circuit, yieldable means engaging said strip and tending to keep the circuit closed, and opposed yieldable means 25 engaging said strip and tending to open the circuit; with a main circuit including the strip and contact, and a shunt circuit for energizing the electromagnet.

30 5. An interrupter for electric currents comprising a tensioned strip adapted to be connected in the circuit, a contact point beside said strip also adapted to be connected in the circuit, an electromagnet beside the 35 strip adapted when energized to attract the strip and open the circuit, yieldable means engaging said strip and tending to keep the circuit closed and opposed yieldable means engaging said strip and tending to open the 40 circuit; with a main circuit including the strip and contact, and a shunt circuit for energizing the electromagnet.

6. An interrupter for electric currents comprising a tension strip, a contact, an 45 armature on said strip, an electromagnet adapted to attract the armature, a device engaging said strip at one side of the armature to keep the circuit closed, and an opposed device tending to open the circuit engaging said strip at the opposite side of the armature, substantially as described.

7. In an interrupter the combination of a strip, means for putting the strip under tension, a contact beside the strip, an electromagnet beside the strip, a device interposed between the magnet and the contact for normally keeping the circuit closed, and a device at the opposite side of the magnet adapted to draw the strip toward the magnet.

60 8. An interrupter for electric currents comprising a pair of contacts, a tension strip carrying one of said contacts, an armature on said strip, an electromagnet adapted 65 to attract the armature, a resilient means

engaging said strip at one side of the armature, and an opposed resilient means engaging said strip at the opposite side of the armature, substantially as described.

9. In an interrupter the combination of a 70 strip, means for putting the strip under tension, a contact carried by said strip, a relatively fixed contact normally impinging the strip contact, an armature on said strip, an electromagnet opposite the armature, a 75 spring interposed between the armature and the contact for normally keeping the circuit closed, and a spring at the opposite side of the armature adapted to draw the strip toward the magnet. 80

10. In combination, a contact device, a tension strip beside such contact, an armature on said strip, an electromagnet adapted to attract the armature, yielding means engaging said strip for holding the circuit 85 closed, and an opposed yielding means engaging said strip and tending to open the circuit; with electric circuit connections with the said contact and strip, and means for conducting current to the magnet. 90

11. In combination, a pair of contacts, a tension strip carrying one of said contacts, an armature, an electromagnet adapted to attract the armature, a spring engaging said strip for holding the contacts together, and 95 an opposed spring engaging said strip to open the circuit; with electric circuit connections with said contacts for passing the main current therethrough, and a shunt circuit for energizing the magnet. 100

12. In combination, a strip, a contact carried by said strip, a relatively fixed contact normally impinging the strip contact, an electromagnet beside the strip, a spring for normally holding the circuit closed, and an opposed spring tending to open the circuit; with main circuit wires connected with said contacts, and a shunt circuit for energizing the magnet. 105

13. In combination, a strip, means for tensioning said strip, a contact on said strip, an adjustable contact adjacent the strip, an electromagnet adjacent said strip, an adjustable spring connected with said strip intermediate the magnet and contact, and an opposed adjustable spring connected with said strip at the opposite side of the magnet; with main circuit wires connected with said contacts, and a shunt circuit for energizing the magnet. 110 115

14. In combination, a strip, means for putting the strip under tension, a contact carried by said strip, a relatively fixed contact normally impinging the strip contact, an armature on said strip, an electromagnet opposite the armature, a spring between the armature and the contact for normally holding the circuit closed, and a spring at the opposite side of the armature tending to draw the armature toward the magnet; with 125 130

main circuit wires connected with said contacts, and a shunt circuit for energizing the magnet.

15. In combination opposite posts, a strip 5 strung between said posts, a contact on said strip, an adjustable contact adjacent the strip contact, an armature on said strip, an electromagnet adjacent said armature, an adjustable spring connected with said strip 10 intermediate the armature and contact, and an opposed adjustable spring connected with said strip at the opposite side of the armature; with main circuit wires connected with said contacts, and a shunt circuit for energizing the magnet.

16. In combination an interrupter comprising a strip, means for putting the strip under tension, a contact carried by said strip, a relatively fixed contact normally 20 impinging the strip contact, an armature on said strip, an electromagnet opposite the armature, a spring interposed between the armature and the contact for normally holding the contact impinged, and a spring at 25 the opposite side of the armature adapted to draw the armature toward the magnet; with a main circuit including said contacts, a switch, a shunt circuit and connections whereby when the switch is adjusted to one 30 position the interrupter magnet is placed in series with the main circuit, and when the switch is adjusted to another position the interrupter magnet is thrown into the shunt circuit.

35 17. In an interrupter for electrical circuits, in combination, an actuating coil, a tension ribbon adapted to be vibrated by the action of said coil, contacts adapted to be opened and closed by the vibration of said 40 ribbon, and a plurality of resilient members operative to regulate the pressure between said contacts and the rate and amount of vibration of said ribbon.

18. In an interrupter for electrical circuits, in combination, an actuating coil, a tension ribbon adapted to be vibrated by the 45 action of said coil, contacts adapted to be

opened and closed by the vibration of said ribbon, and a plurality of resilient members connected to said ribbon and operative to 50 regulate the pressure between said contacts and the rate and amount of vibration of said ribbon.

19. In an interrupter for electrical circuits, in combination, an actuating coil, a tension ribbon adapted to be vibrated by the action of said coil, contacts adapted to be opened and closed by the vibration of said ribbon, and a plurality of springs operatively connected to said ribbon, one of 60 which operates to regulate the pressure between said contacts and coöperates with another to govern the rate and amount of vibration of said ribbon.

20. In an interrupter for electrical circuits, in combination, an actuating coil, a tension ribbon adapted to be vibrated by the action of said coil, contacts adapted to be opened and closed by the vibration of said ribbon, and a plurality of adjustable springs 70 operatively connected to said ribbon, one of which operates to regulate the pressure between said contacts and coöperates with another to govern the rate and amount of vibration of said ribbon.

75 21. In an interrupter for electrical circuits, in combination, an actuating coil, a tension ribbon mounted between two supports, an armature centrally mounted on said ribbon by means of which the same is 80 vibrated by the action of said coil, a pair of springs connected to said ribbon on either side of said armature, and contact members, one of which is positioned on said ribbon between one of said springs and the support at 85 that end of said ribbon.

In testimony that I claim the foregoing as my own, I affix my signature in presence of two witnesses.

EMILE BACHELET.
